(Cl. D57—1)

To all whom it may concern:

Be it known that I, Donald M. Mackenzie, a citizen of the United States, residing at Reading, in the county of Berks and State of Pennsylvania, have invented a new, original, and ornamental Design for a Handling Support for Treating Lenses, of which the following is a specification, reference being had to the accompanying drawing, forming part thereof.

Fig. 1 is a perspective view of a handling support for treating lenses, showing my new design.

Fig. 2 is a plan view of the same, and

Fig. 3 is a side elevational view thereof.

I claim:

The ornamental design for a handling support for treating lenses, substantially as shown.

DONALD M. MACKENZIE.
